UNITED STATES PATENT OFFICE

ALLEN P. ASHER, OF SANDPOINT, IDAHO

TOOL FOR REMOVING DENTS FROM METALLIC BODIES

Application filed October 29, 1929. Serial No. 403,248.

This invention relates to tools for removing dents from metallic bodies, more particularly automobile fenders, doors or other portions of an automobile body.

5 The primary object of the present invention is to provide a tool which may be securely attached to the body to be worked upon such for example as a motor vehicle fender, or to a suitable adjacent support and 10 operated against the inner surface of the body to force outwardly any indentations therein so that the outer surface of the body will be restored to its original contour.

Another object of the invention is to provide 15 a dent removing tool for metallic bodies which includes a rolling element adapted to be moved over the dented surface against the convex portion thereof, in an arc applying rolling pressure thereto for the purpose 20 of restoring the dented portion to its normal or original position.

Still another object of the invention is to provide a dent removing tool which is adapted 25 to work against the bead of a motor vehicle fender for the removal of dents therefrom.

The invention broadly contemplates the provision of a supporting frame in which is oscillatably mounted a block through 30 which extends a shaft, the shaft being in threaded engagement with the block so that it may be fed therethrough as desired to position a mandrel wheel carried upon the inner end properly with respect to a dent 35 in the adjacent body. The block carrying the shaft is so mounted that the shaft may be swung in a plane at right angles to the block and the block supporting frame is so mounted as to permit its oscillation in a 40 plane transversely of the plane in which the shaft is swung.

The invention will be best understood from a consideration of the following detailed description taken in connection with 45 the accompanying drawings forming part of this specification, with the understanding, however, that the invention is not confined to any strict conformity with the showing of the drawings but may be 50 changed or modified so long as such changes

or modifications mark no material departure from the salient features of the invention as expressed in the appended claims.

In the drawings:

Figure 1 is a view in transverse section 55 through a motor vehicle fender showing the device embodying the present invention applied thereto.

Figure 2 is a front elevational view of the 60 supporting frame for the tool.

Figure 3 is a face view of the mandrel roller.

Referring more particularly to the drawings wherein like numerals of reference indicate corresponding parts throughout the 65 several views, the tool embodying the present invention is shown as applied to a motor vehicle fender, the fender being indicated generally by the numeral 1, the outer edge or rim portion thereof being indicated by 70 the numeral 2.

The tool comprises a relatively long frame 3 which is made up of a straight bar 4 and a bowed bar 5 which extends longitudinally thereof and which has the ends turned inwardly as indicated at 6 and attached to the straight bar 4 adjacent the ends of the same in the manner shown, the extended end portions of the bar 4 being slightly reduced 75 and of circular cross-section as indicated 80 at 7.

At each end of the bar 4 a clamp 8 is mounted. These clamps are preferably of the type known as "C" clamps, those used in association with the present tool preferably having a relatively deep throat. The frame of each of the clamps 8 is provided with a series of transverse apertures 9 in one of which the reduced portion 7 at one 85 end of the bar 4 is adapted to position, the clamp being prevented from disengagement from the bar by a nut or by any other suitable means.

Removably positioned in each of the bars 95 4 and 5 midway between the ends of the frame are bearing points 10 which as shown are directly in alignment transversely of the frame and oscillatably mounted between these bearing points is a block 11 through 100

the central portion of which a threaded passage 12 is formed.

Extended through the block 11 and having engagement with the threads of the passage thereof is a mandrel operating bar 13, substantially half of this bar being threaded as indicated at 14 and that end from which the threads extend being reduced to form the pin 15.

10 Rotatably mounted upon the pin 15 is a mandrel wheel 16 the contour of the periphery thereof being substantially arcuate as indicated at 17. While the periphery of this wheel is as stated substantially arcuate in cross-section the arc is so disposed that a rounded outer edge is provided as indicated at 18 while at the inner side of the wheel an edge is provided which is relatively sharp as indicated at 19. The face of the wheel 16 may be recessed as at 20 so that a holding device such as the cotter pin 21 which passes through the pin 15 will be disposed below the outer surface of the wheel.

25 From the foregoing description taken in association with the accompanying drawings it will be readily seen that in employing the present tool for the removal of a dent from a motor vehicle fender the frame 3 is first disposed beneath the free edge 2 of the fender so that the clamps may receive and engage the same. The position of the frame 3 may be adjusted between the clamps by engaging the ends 7 of the bar 4 thereof in the apertures 9 of the clamps where it 30 will be supported to the best advantage for removing a dent. The bar 13 may then be rotated to move the mandrel wheel 16 inwardly or outwardly as desired to position it beneath the dent after which the frame 35 may be oscillated by pressing down upon the outer end of the bar to bring the roller into contact with the dented fender surface. Removal of the dent is then effected by swinging the bar 13 between the pivot points 10 so as to roll the wheel 16 over the dented 40 surface in an arcuate path.

45 By using the present tool dents may be easily and quickly removed without the usual hammering or the application of pressure of any kind to the outer or finished surface of the fender so that the contour of the fender is restored without marring the finish thereon.

Having thus described my invention, what I claim is:

50 1. A tool for removing dents from metallic bodies comprising an elongated frame, clamp elements designed to pivotally connect with the ends of said frame, a pair of pivot elements carried by the frame, a block member oscillatably mounted between the pivots, a bar extending through said block, a mandrel roller rotatably carried upon one end of said bar, and a screw thread connection between said bar and said block permitting adjustment of the bar transversely of the block.

55 2. A tool for removing dents from metallic bodies comprising an elongated frame, clamp elements designed to pivotally connect with the ends of said frame, a pair of pivot elements carried by the frame, a block member oscillatably mounted between the pivots, a bar extending through said block, and a mandrel roller rotatably carried upon one end of said bar, said roller being formed to provide a sharp peripheral edge and a rounded peripheral edge.

60 3. A tool for removing dents from metallic bodies comprising an elongated frame, clamp elements designed to pivotally connect with the ends of said frame, a pair of pivot elements carried by the frame, a block member oscillatably mounted between the pivots, a bar extending through said block, a mandrel roller rotatably carried upon one end of said bar, and a screw thread connection between said bar and said block permitting adjustment of the bar transversely of the block, said roller being formed to provide a sharp peripheral edge and a rounded peripheral edge.

65 4. A tool of the character described, comprising an elongated frame, a pair of trunnions carried by and disposed at opposite sides of said frame, a pair of U-clamps each having an aperture through the body thereof for the reception of a trunnion, a pair of oppositely directed pivot members carried by said frame, a block disposed between and engaged by said members, a bar extended through and in threaded connection with said block, and a mandrel roller mounted upon said bar.

70 5. A tool for removing dents from a sheet metal body, comprising a frame, means for securing the frame in working position to an edge of the body and having a laterally opening gap to receive said edge, whereby swinging of the frame transversely of the edge is permitted, a bar extending transversely of and supported to swing transversely of the swing of the frame, and a pressure applying head carried by the bar so as to make rolling contact with the work.

75 6. A tool for removing dents from a sheet metal body, comprising a frame, means for securing the frame in working position to an edge of the body and having a laterally opening gap to receive said edge, whereby swinging of the frame transversely of the edge is permitted, a bar extending transversely of and supported to swing transversely of the swing of the frame, a pressure applying head carried by the bar so as to make rolling contact with the work, and means for adjustably shifting said bar transversely of the supporting frame.

80 7. A tool for removing dents from a sheet metal body, comprising an elongated frame,

support engaging clamps oscillatably carrying said frame and adapted to grip an edge of the body, a body oscillatably carried by the frame, a bar carried by and longitudinally adjustable with respect to said oscillatable body and extending transversely of the frame, and a roller mandrel carried by said bar for applying pressure to the metal body.

8. A tool for removing dents from a sheet metal body, comprising a clamp adapted to grip an edge of the body, a frame pivotally attached to the clamp to suspend therefrom and swing transversely of the adjacent body edge, a member pivotally supported by the frame to oscillate about an axis at right angles to the pivotal axis of the frame, a bar extending through and longitudinally shiftable in the member, and a rotatably mounted element at one end of the bar for application to the dented face of the metal body.

In testimony whereof I hereunto affix my signature.

ALLEN P. ASHER.
